Primary Examiner — Kelley Donnelly(74) *Attorney, Agent, or Firm* — Erickson Kernell Derousseau & Kleypas LLC(57) **CLAIM**

The ornamental design for an arm piece pad cover, as shown and described.

DESCRIPTION

FIG. 1 is a perspective view of an arm piece pad cover according to the present invention;

FIG. 2 is a front view thereof, the rear view being a mirror image;

FIG. 3 is a top plan view thereof;

FIG. 4 is a right side view thereof, the left side view being a mirror image; and,

FIG. 5 is a bottom plan view thereof.

The broken lines showing in FIGS. 1, 2, and 5 in the drawings are for the purpose of illustrating the environment of the design only and form no part of the claimed design.
